United States Patent Office

Des. 230,407
Patented Feb. 19, 1974

230,407

DATA PROCESSOR TERMINAL

Lewis Greenwood, Tarzana, Calif., assignor to Pay Fone
Systems, Inc., North Hollywood, Calif.

Filed Dec. 26, 1972, Ser. No. 317,933

Term of patent 14 years

Int. Cl. D14—03, 01

U.S. Cl. D26—14 A

FIG. 1.

FIG. 2.

FIG. 3.

FIG. 4.

FIG. 5.

FIG. 1 is a top plan view of a data processor terminal incorporating my new design.

FIG. 2 is a front elevational view thereof.

FIG. 3 is a right side elevational view thereof.

FIG. 4 is a left side elevational view thereof.

FIG. 5 is a rear elevational view thereof.

I claim:

The ornamental design for a data processor terminal, substantially as shown and described.
